[57] CLAIM

The ornamental design for a syringe plunger for an IV infusion pump, substantially as shown and described.

DESCRIPTION

FIG. 1 is a front perspective view of a syringe plunger for an IV infusion pump embodying our new design;

FIG. 2 is a top plan view thereof;

FIG. 3 is a left end elevational view thereof;

FIG. 4 is a right end elevational view thereof;

FIG. 5 is a bottom plan view of the syringe plunger in the orientation shown in FIGS. 1 and 2;

FIG. 6 is a back view of the syringe plunger showing the side opposite that shown in FIG. 1; and

FIG. 7 is a cross-sectional view taken along line 7—7 of FIG. 1.

Fig. 2
